PRESSING MACHINE FOR PANTS
AND THE LIKE

Howard O. Bayler, Los Angeles, Calif.

Application February 21, 1948, Serial No. 9,996

5 Claims. (Cl. 38—21)

1

This is an invention for a new type of clothes pressing device. The particular type illustrated being designed for pressing trousers, pants, and the like, in which the trousers are hung in an inverted manner at its cuff's end between a central mandrel and a pair of hinged wing-like mandrels. The waist portion of the trousers is clamped over a special drum-like mandrel or holder and the entire trousers kept taut or distended until its treatment is terminated by the application of steam, hot air, and vacuum.

The base of the device is furnished with all the necessary mechanism etc., but only the connection means are accoutered for supplying live steam and for draining away unwanted fluids. The entire device is compact and can be placed in a much smaller floor space than any of the known horizontal types of pressing devices.

One of the principal objects of this invention is to present a new and novel vertical type of pressing device for trousers and the like which is a complete unit for doing a complete job with a minimum of parts.

Another object is to provide a vertically arranged pressing device and the like which is equipped with a base having a portion extending upwardly therefrom for telescoping the waist portion of a pair of pants and another portion extending upwardly therefrom which supports a central mandrel having wing-like mandrels on either side thereof, the pressing device being simple and sturdy in construction, easy and simple to operate, and economical to make and manufacture.

Other objects, advantages and features of this invention will appear from a perusal of the accompanying drawings, the subjoined detailed description, the preamble of these specifications, and the appended claims.

Applicant is now about to describe one of the preferable forms of his invention in order to teach those skilled in the art how to make and use the same, but it is to be understood that the drawings and description thereof are not to limit the invention in any sense whatsoever except as specifically limited by the appended claims.

In the drawings:

Figure 1 is a side elevational view of the device of this invention, as illustrated, with parts broken away to show some internal structure,

Figure 2 is a front elevational view thereof with parts broken away,

Figure 3 is an enlarged sectional view with parts in elevational view showing details of the lower portion of the device,

2

Figure 4 is an enlarged sectional view of Fig. 1 taken substantially along the line 4—4 of this figure,

Figure 5 is an enlarged side elevational view of the means for holding the cuff ends of pants and the like,

Figure 6 is an edge elevational view of that shown in Figure 5.

Figure 7 is a vertical sectional view, parts in elevation, taken along the line 7—7 of Figure 3, but shown on a somewhat smaller scale.

This invention, in the particular form illustrated, is composed of the following principal parts: the base indicated at 1 which is the main support for the entire device and which is hollow for housing the various operating mechanism, the standard or upright hollow arm means 2, the trousers' receiving and pressing unit 3, and the trousers main supporting means 4 with its hanger-like means 5.

The base has the outer shell or wall means 6 which is curved and provided with the front grilles opening 7 to allow atmospheric air to enter the chamber 8 of the base. The top portion of the base is stepped inwardly toward its center and has the rounded portion 9, the sharp angled portion 10, and the tapered portion 11 with the top opening 12 which is screened. The base has the bottom floor 13 which has a pair of openings to accommodate the pair of steam pipes 14 and 15, one being the pressure side and the other the return, and the opening 16 to accommodate the exhaust pipe or duct 17 of the centrifugal air pump 18, as shown.

The hollow arm 2 has its bottom end portions welded or otherwise fixed to the shell of the base and its top end portions offset forwardly and fixed securely to the bottom portions of a hollow central mandrel element or buck 19. This mandrel element is hollow and the walls thereof perforated, as shown, and the outer side of these walls are provided with a suitable fabric or cloth or padding against which the trouser legs are pressed. The bottom of the mandrel is shown as having a catch basin-like floor 20 and a drain pipe 21 therefor which runs through the arm 2 and through the floor of the room to a soil pipe, not shown.

A steam pipe 22 is connected with the hollow chamber of the central mandrel 19 and also to one side of a three-way fluid valve 23, which valve receives its steam from a branch pipe 24 connected with a top portion or any portion of the steam pipe radiator 25. Another pipe, a short curved nipple with a flared end, is shown at 26 which is connected also to the valve 23. And

another pipe 27 is connected to the valve 23 and runs upwardly through the arm 2 and is terminated by a T-connector 28 that supplies the flexible branch pipes 29 and 30 with steam.

On each side of the central mandrel 19 are the two side mandrels, pressing heads or wings 31 and 32 which are hollow and their inner walls perforated and covered with a suitable fabric or pad which is common in the pressing art. Each side wing or hinged mandrel has an integral arm 33 which extends outwardly and makes a pivot connection 34 with a similar arm 35 which extends from the top of the hollow main supporting arm 2, as shown. The flexible pipes 29 and 30 make good connection with their respective winged-mandrels. These wings are each provided with a long vertical handle 36 and a suitable clamping means 37 so that both wings can be pressed and locked against the central mandrel 19. The valve 23 may be any type of steam valve now obtainable in the market which is operated by a stem 38 having the handle 39; in one position, the valve allows steam to enter pipe 22 and be conducted to the central mandrel 19, in another position, steam is allowed to enter pipe 27 and be conducted to both wing mandrels, and in still another position or part turn of the stem of the valve, steam is allowed to enter the pipe 26 and be dispersed upwardly and outwardly through the opening 12 and hence through the waist portion of the pants being pressed.

Note, as shown best in Figure 4 of the drawings, that the central mandrel 19 is substantially ovate or oval-like shape in horizontal cross section and that the outer mandrels or wings 31 and 32 are concaved on their inner faces so as to coincide with the contour of the outer walls of the central mandrel so that all parts of the pants which lie between them are given equal pressure when the two wings are locked in position. The top end or cuff ends of the pants are engaged by the pair of hangers 5 and these hangers can be pulled downwardly so that they enter the pressing device between the wings 31 and 32 and the central mandrel 19. The hangers are made of thin material, for instance thin metal, and do not in any way interfere with proper pressing of the cuffs of the pants. The hangers are positioned on each side of a main supporting stem 40 which has a hook 41 that is entered into a loop at the end of a cable or cord 42. This cable passes through the hollow rod or pipe 4 and at the end thereof is fixed a weight 43 in the vertical straight portion of the pipe 4; thus the hangers can be pulled downwardly and made to enter the pressing device, and when they are released, the pants attached thereto will promptly rise and free themselves from the mandrels and also from the drum-like means or mandrel 11 when the clamps 44 are opened; these clamps 44 holding the pants about the belt portion thereof. When the pants are properly placed in position on the central mandrel, the crotch portion thereof will snugly engage the bottom portion 19' of the mandrel.

Each pants hanger is alike, and consists of the similar parts now to be explained. The shank or stem 40 has an axial slot in which rides a pin 46 and this pin pivotally supports on each side of the shank a pair of arms 47 and 48. These arms are limited in their outward movement by the pivoted links 49 and 50 which have their overlapped ends pivoted to the bottom of the shank at 51, and their distal ends pivoted to a central portion of the arms 47 and 48 respectively as shown at 52 and 53. Each arm has a serrated

end 54 which is designed to engage the cloth portions of the pants and hold them.

In chamber 8 of the base, there is mounted a suitable electric motor 55 upon the supporting means 56. The shaft of the motor is indicated at 57 and it has keyed thereto the armature of the centrifugal blower 18, the air inlet to the blower being around the shaft itself which is provided with the inlet duct 58 having the flared shell 59 which opens onto the steam coil or radiator 25. At one side of the inlet duct 58 there is a duct 60 closable by the valve 61. This duct 60 conducts hot air from and provides a vacuum in the central mandrel 19 when the valve 61 is open; when such a vacuum is created, the bottom outlet duct 17 is utilized as its valve 62 is connected so as to open when the valve 61 is open.

When the pants are hanging in the device, one leg thereof is placed between the center mandrel and the outer mandrel 31 and the other leg placed between the center mandrel and the outer mandrel 32, the belt portion of the pants is then telescoped onto the tapered walls 11 and held snug thereto by the spring clamps 44; there being four such clamps evenly spaced around the wall 11.

There are two foot pedals or treadles indicated at 70 and 71 which are pivoted to the front of the shell covering and which are spring controlled for their return to upward positions when not being manually compressed. Each one of these pedals is attached to a "Bowden wire" (encased wire) 72, the casing of which is firmly anchored to the floor of the chamber 8. The wire of pedal 71 is attached to a crank member 73 and this crank member is linked to another upper crank member 74 by the rod 75, as shown, so that compression of the pedal 71 will cause opening of valve 61 and closure of valve 62, thus forcing heated air through the waist portion of the pair of pants via tapered section 11. The other pedal 70 has its wire 72, see Fig. 7, attached to a crank member 76 which is keyed to a journalled rod 77 and this rod has another crank member 78 keyed thereto. The crank member 78 is connected to a shiftable rod or pin 79 which is attached to a shiftable valve element 80, as shown. The valve head 80 rides along the shaft 57 which is provided with a slot 57' thru which the pin 79 works. Note, that when the pedal 70 is depressed, the rod 77 is rotated and the valve 61 opened as the valve 80 is closed so that the center mandrel can be placed under a vacuum when desired. Means may be provided for raising and lowering the member 11 by pedal so that various lengths of pants can be accommodated.

The manner in treating the pants is as follows: 1st. The legs of the pants are steamed via center mandrel 19 with the winged mandrels in open positions; 2nd. The winged mandrels are closed and the pants legs are steamed via the wing mandrels only; 3rd. The waist portion of the pants is steamed; 4th. Hot air is blown through waist only; and 5th. The legs only of the pants are vacuumed through the center mandrel only. The pants are then removed from the machine in a clean and neatly pressed condition.

It is, of course, understood that various changes and modifications may be made in the details of form, style, design, and construction of the whole or any part of the specifically described embodiment of this invention without departing from the spirit thereof; such changes and modifications being within the scope of the following claims.

I claim:

1. In a device for pressing trousers and the like, the device having a base with means at the top thereof adapted to receive the open waist portion of an inverted pair of pants, a standard extending upwardly from one side of the base, an elongated vertically arranged central mandrel supported by the standard over the base and which mandrel is configurated to receive a pants' leg on each side thereof and the crotch of a pair of pants at the bottom thereof, and a pair of outer mandrels hingedly supported by the standard which are adapted to close-in the central mandrel and press pants legs.

2. The device recited in claim 1 wherein an arm is fixed to the base and has a portion thereof of supporting a pants hanger over the central portion of the central mandrel.

3. The device recited in claim 1 wherein the base has arm means extending therefrom with an end thereof supporting a pants supporting unit which is adapted to hold the cuff ends of a pair of pants.

4. In a pressing device for pants and the like, the device having a base with a bracket extending upwardly therefrom at one side thereof, clamping means at the top of the base surrounding a tapered section which is adapted to receive and hold the waist portion of an inverted pair of pants to be pressed, a vertically extending central mandrel fixed to the top of the bracket, and

5 a winged mandrel on each side of the central mandrel which winged mandrels are hinged to the top of the bracket, means for supplying hot air through the top of the base and means for supplying steam through the top of the base, means for supplying steam to the central mandrel and the winged mandrels, and means for placing the central mandrel under vacuum.

10 5. In a pants pressing device having a base with an upright standard fixed thereto, the standard having an offset portion at the top thereof with a vertical edge, an upright buck fixed to said edge portion of the standard and arranged to accommodate a pants' leg on each side thereof, a vertical pressing head on each side of said buck hinged to said offset portion of the standard, said pressing heads adapted to be clamped against said buck.

HOWARD O. BAYLER.
